MEANS FOR INTRODUCING A PRESSURIZED FLUID INTO AN INTERNAL COMBUSTION ENGINE COMBUSTION CHAMBER THROUGH THE SPARK PLUG OPENING

Alfred Candelise, Flint, Mich., assignor to General Motors Corporation, Detroit, Mich., a corporation of Delaware

Application May 24, 1961, Ser. No. 112,449, which is a division of application Ser. No. 12,857, Mar. 4, 1960, now Patent No. 3,073,298, dated Jan. 15, 1963. Divided and this application Feb. 4, 1963, Ser. No. 255,749

3 Claims. (Cl. 313—120)

This is a division of my copending application Serial No. 112,449, entitled "Means for Introducing a Pressurized Fluid Into an Internal Combustion Engine Combustion Chamber Through the Spark Plug Opening," filed May 24, 1961 which in turn is a division of my application Serial No. 12,857, entitled "Means For Burning Hydrocarbons in an Internal Combustion Engine Cylinder," filed March 4, 1960, now Patent No. 3,073,298.

The invention relates to a mechanism for more completely burning the hydrocarbons introduced into the cylinders of an internal combustion engine during engine operation. It particularly concerns the burning of the hydrocarbons which normally remain in the unburned state for various reasons and pass out of the engine through the exhaust system.

During the operation of internal combustion engines of the type normally employed in automotive vehicles, for example, a charge of fuel and air mixture is introduced into an engine cylinder and is compressed. The charge is ignited and burning of the fuel takes place. It has been found that much of the fuel remains in the unburned state, however, and is discharged through the engine exhaust system to the atmosphere. This particularly occurs during engine idling conditions. One of the reasons for the incomplete burning is that there is insufficient air within the combustion chamber to permit complete combustion of all of the fuel introduced. During engine idling the fuel-air charge must be rich in fuel in order to ignite. Excess fuel is therefore provided for this purpose.

The unburned hydrocarbons which are discharged to the atmosphere contribute materially to the atmospheric contamination condition commonly referred to as smog. They also represent a loss in overall efficiency since the energy normally contained therein is not utilized. It has been found that compressed air may be introduced into the combustion chamber of the engine at desirable times and under desirable pressures so as to more completely burn the hydrocarbons contained therein. This results in greater efficiency and also materially reduces the amount of unburned hydrocarbons being discharged to the atmosphere. It has been found that the amount of carbon monoxide which was formerly present in the exhaust gases of such engines can be substantially eliminated by complete combustion in this manner. This eliminates an important danger to the occupants of such vehicles since it is well known that carbon monoxide is poisonous and detection of its presence in the passenger section of the vehicle is not readily accomplished. The introduction of compressed air during the latter portion of the normal combustion period and continuing through at least portion of the power stroke also results in lowering the temperature and amount of the exhaust gases left in the combustion chamber at the time of the intake valve opening, so that the volumetric efficiency of the engine and the combustion efficiency are increased. This results in increased power output of the engine and improved detonation characteristics. These benefits can be attained while utilizing a compressed air source driven

2

by the engine capable of continually delivering air at a minimum gauge pressure of 30 p.s.i. and in a rate range of 0.5 to 1 c.f.m. per engine cylinder while the engine is operating at idle and low speed conditions.

It has long been proposed to introduce air under pressure during the latter portion of the expansion cycle of engines of this nature in order to obtain additional power from the energy represented by the pressure of the air. It has also been known to introduce compressed air during the combustion portion of the cycle in order to augment the burning gases to give a second expansion and to permit the burning gases to heat the compressed air so introduced to increase the expansion of that air and thereby increase the power of the engine. Systems of this nature are disclosed in United States Patents 1,430,480, Whaley and 1,904,755, Barthomew, for example. The structure disclosed by these patents, however, did not yield sufficiently satisfactory results to warrant their use. This was due to various reasons including the type of air compressor mechanism used or available to furnish the air and type of mechanism used to introduce the air into the engine cylinder at the proper time. A system of this nature requires a source of air under pressure which will deliver sufficient quantities at sufficient pressures to accomplish the desired results.

Mechanisms embodying the invention to which my aforementioned applications are directed provide for the introduction of the air at positions relative to the combustion chamber and the fuel-air mixture contained therein which increase the burning efficiency of the fuel. They also provide for proper timing of the air relative to the various cylinders of a multi-cylinder engine so that maximum benefits from the introduction of the air into the combustion chambers may be realized. They include a system having a source of air connected to an air timing and distribution mechanism which will distribute the air to each cylinder at the proper time and in the proper quantities, and also include structures for the introduction of air so timed into each cylinder so as to provide improved air distribution characteristics within the cylinders. These structures include modified spark plugs and fittings which are utilized in conjunction with standard spark plugs. The present invention is particularly directed to certain forms of the modified spark plug structures clearly shown in the drawings wherein:

FIGURE 1 is a sectional view of the modified spark plug showing the associated air introduction mechanism;

FIGURE 2 shows a further modification of a spark plug for introducing air into an engine combustion chamber;

FIGURE 3 is an enlargement of a portion of FIGURE 1 showing the valve position of the air introduction mechanism when air is being introduced into the engine combustion chamber; and

FIGURE 4 is an end view of the air outlet end of the mechanism of FIGURE 1 as viewed in the direction of arrows 4—4 of that figure.

The air injection system described in my copending application is discussed in connection with a V-8 type engine having parallel banks of cylinders. The engine is provided with any well known fuel-air induction system and exhaust gas system. Each cylinder is provided with a modified spark plug which ignites the fuel-air mixture in the cylinder combustion chamber in the well known manner as well as providing for air injection. The spark plugs are connected to ignition wires and to distributor, which may be of any well known type, for properly timing the ignition sparks of the various spark plugs. As is the common practice, the distributor driven in timed relation with the engine crankshaft. A source of compressed air is

provided in the said system which may be driven by the engine. Conduits deliver air from the compressed air source to a rotary air distribution and timing valve mechanism which is mounted adjacent the engine and driven in timed relationship with the engine combustion cycles. From the rotary valve mechanism the compressed air is delivered by separate pressure lines to each combustion chamber through an air manifold along each bank of cylinders which in turn distributes the compressed air to the modified spark plug air injector means. This invention has to do with the air injector means which will now be described.

FIGURE 1 shows one form of the air injector means. A spark plug, used to ignite the fuel-air mixture in the combustion chamber, is also used to introduce compressed air into the engine cylinders. In this form the compressed air is introduced through the interior of the spark plug with the air connection being made adjacent the spark plug terminal. A check valve is provided as an integral part of the spark plug.

The spark plug 4 includes a terminal 6 and an insulation shell 8, a metallic shell 10 in which the insulation shell is mounted, an inner electrode 12, an outer electrode 14, and various elements providing an electrical connection from the terminal 6 to the electrode 12 through the insulation shell 8. The terminal 6 is adjacent to a fitting 16 to which an air line (not shown) from the rotary distribution valve may be attached as provided for in my other applications. In the construction illustrated, fitting 16 is provided with an annular flange section 18 through which the lower portion of terminal 6 extends in order to attach the fitting to the main body of the spark plug. A valve seat member 20 is provided with interior threads into which the lower end of terminal 6 is threaded to hold fitting 16 and the terminal in place. This arrangement also electrically connects terminal 6 to member 20. Gaskets 32 and 34 are provided on either side of the fitting flanged section 18 to prevent leakage of air. Fitting 16 has a passage 36 which connects with the terminal-receiving opening in flanged section 18. Terminal 6 has a longitudinal passage 38 and a radially extending passage 40 which conduct air from fitting 16 to the interior of valve seat member 20. The lower end 42 of the valve seat member is provided with a conical section inner surface 44 of which acts as the seat for check valve 46. Passage 48 in member 20 connects terminal passage 38 with one side of the valve 46. A spring seat 50 is formed on the interior surface of passage 48 and a coiled compression spring 52 is received on the opposite side of seat 50 from the valve 46. Details of this portion of the structure are best seen in FIGURE 3. Spring 52 acts against spring seat 54 which is attached to valve 46 by rod 56 so that the spring urges valve 46 to the closed position against surface 44. Spring seat 54 is provided with several openings 58 through which air may pass during the operation of the mechanism. Valve 46 is illustrated as having a cup formation with a tapered section 60 mating with surface 44 of valve seat 20. The valve is also provided with a generally cylindrical portion 62 which extends below the end of valve seat 20 and into valve chamber 64. Apertures 63 are formed in the walls of portion 62 to permit air flow beyond the valve when the valve is fully opened in the position illustrated in FIGURE 3. Chamber 64 is formed in sleeve 66. This sleeve acts as a mount for member 20 and also as an electrical conductor for the electrical operation of the spark plug. Valve seat member 20 is threaded into the upper end of sleeve 66. Valve chamber 64 is connected to a passage 68 leading through sleeve 66 to conduct compressed air which passes member 20 onward into the combustion chamber. The reduced end 70 of sleeve 66 is secured within the insulation shell 8 and passage 72 is sealed by a seal 74. The upper end 76 of inner electrode 12 is flared at 78 to extend into passage 72 and locate the position of the inner electrode in the insulation shell 8. Tubular member 80 is secured within the passage 68 of sleeve 66 in a suitable manner such as

by press fitting or brazing. An enlarged head 82 is provided at the lower end of member 80 and this head engages the flared end 78 of electrode 12 to seal the air passage provided by passages 84 and 86 through member 80 and electrode 12, respectively. The lower end of electrode 12 is provided with an enlarged head 88 at the terminal end of passage 86. Openings 90, 92, 94 and 96 are provided in head 88 so that they connect with passage 86 and extend angularly downward and outward. These openings discharge the compressed air into the combustion chamber of the engine. Although four openings are illustrated, a different number of openings may be used if desired. In the construction best seen in FIGURE 4 it may be noted that opening 94 discharges air so that it impinges upon other outer electrode 14, thereby assisting in keeping that electrode clean and also having a cooling effect on it. The air discharged through the electrode openings passes into the combustion chamber in a conical spray pattern to provide effective air delivery.

The modification shown in FIGURE 2 is generally similar to the modification illustrated in FIGURE 1 but is somewhat simplified in construction. The spark plug terminal 98 is integrally formed with the air line fitting 100 and is threaded into the insulation shell 102. An air passage 104 connects with the valve spring chamber 106 contained within the shell 102 and the valve seat sleeve 108. Valve 110 has a hollow stem 112 which is mounted for reciprocation in the closed end 114 of sleeve 108. A valve stem guide 116 is secured within the sleeve 108. Valve spring 118 seats against a shoulder formed inside sleeve 108 and reacts against spring seat 120 which is mounted on the upper end of valve stem 112. Openings 122 are provided within spring seat 120 to prevent entrapment of air in the portion of chamber 106 occupied by spring 118. The lower end of chamber 106 underneath guide 116 is vented to the atmosphere through passage 124 in sleeve 108 and a mating passage 126 extending through shell 102. The closed end 114 of sleeve 108 is provided with a valve seat 128 against which the valve is urged by spring 118. Several orifices 130 extend through the wall of the hollow valve stem 112 immediately adjacent the valve seat 128 so that air is available at the valve seat 128 to keep the seat clear of foreign matter when the valve is opened. Since air passing through orifices 130 is received within seat chamber 132 when the valve is closed, a larger area is provided on which the compressed air acts and tends to open the valve against the forces of spring 118.

The outer electrode 134 of the spark plug is attached to the spark plug metal shell 136 in the conventional manner. The inner electrode 138 is provided as a hollow tube which extends through and below the end of insulation shell 102 to a point adjacent the electrode 134 to establish the spark gap of the plug. The upper end 140 of the tubular electrode 138 is outwardly flared and in engagement with the lower end of sleeve 108 through a washer 142 to provide electrical contact from terminal 98 to the electrode 138.

When valve 110 is opened, air passes through passage 104 and chamber 106 into the hollow stem 112 of the check valve. The air then passes through orifices 130. When the valve is opened only a slight amount the air passes through chamber 132 and then through the inner electrode passage 144. As the valve is opened to the full extent, the air may pass directly from orifices 130 into the electrode passage 144. The air is discharged through the end 146 of electrode 138 and some of the air passes over outer electrode 134, tending to clean and cool that electrode. The outer electrode 134 also acts to break up the air flow and disperse the compressed air throughout the combustion chamber.

I claim:

1. A spark plug assembly for an internal combustion engine having means for introducing compressed air into the combustion chamber of the engine, said spark plug assembly comprising a hollow insulation shell,

a spark plug terminal for receiving the spark plug electrical lead and having an air inlet passage formed therein, said spark plug terminal being mounted within the upper portion of said hollow insulation shell, a hollow center electrode extending into the lower end of said insulator shell, 5
 a check valve assembly between said terminal and said electrode comprising a check valve, a hollow valve stem connected to said check valve whereby air pressure passing from said terminal through said stem is applied against the check valve at the base of said stem, 10
 an annular check valve chamber positioned adjacent said hollow valve stem and immediately above said check valve, said hollow stem having a plurality of orifices through the walls thereof in communication with said check valve chamber, said chamber being adapted to receive air through said orifices for applying air pressure against said check valve within said chamber, 15
 said check valve assembly being adapted to be opened in response to air pressure supplied through said terminal air inlet passage whereby air is injected in the combustion chamber through said center electrode. 20
 2. A spark plug assembly for an internal combustion engine having means for introducing compressed air into the combustion chamber and the engine, said spark plug assembly comprising a hollow insulation shell, 25
 a spark plug terminal for receiving a spark plug electrical lead and having air inlet passage formed therein, said spark plug terminal being mounted within the upper portion of said hollow insulation shell, said air inlet passage being in communication with the hollow portion of said insulation shell, 30
 a hollow center electrode extending into the lower end of said insulation shell, 35
 a check valve assembly comprising an electrical conductive sleeve within said hollow shell in electrical contact with said terminal and said electrode and having a valve seat, 40
 a check valve engageable with said valve seat, a hollow valve stem connected to said check valve whereby air passing through said terminal to said stem is applied against said check valve at the base thereof, 45
 guide means associated within said sleeve for supporting said stem for reciprocable movement, an annular check valve chamber positioned adjacent said hollow valve stem and immediately above said check valve, said hollow stem having a plurality of orifices through the walls thereof in communication with said chamber, said chamber being adapted to receive air through said orifices for applying air pressure against said check valve within said chamber, 50
 said check valve assembly being adapted to be opened in response to air pressure supplied through said terminal air inlet passage whereby air is injected into the combustion chamber through said center electrode and said spark plug. 55

minal air inlet passage whereby air is injected in the combustion chamber through said center electrode. 3. A spark plug assembly for an internal combustion engine having means for introducing compressed air into the combustion chamber thereof, said spark plug assembly comprising a hollow insulation seal, 5
 a spark plug terminal for receiving the spark plug electrical leads and having an air inlet passage formed therein, said terminal being mounted within the upper portion of said insulation seal, said air inlet passage being in communication with the hollow portion of said seal, a hollow center electrode extending into the lower end of said insulation seal, 10
 a check valve assembly between said terminal and said electrode comprising a check valve having frustoconical seating surfaces and a hollow supporting stem having abutment means at the end thereof, an electrical conductive sleeve having a valve seat positioned within said shell between said terminal and said electrode, the stem of said check valve being positioned within said sleeve and said valve being adapted to sealingly engage said valve seat, an annular check valve chamber within said sleeve positioned adjacent said stem and said valve seat, said valve forming a wall of said chamber when in a closed position, said stem having a plurality of orifices through the walls thereof whereby the interior of said stem and said chamber are in communication with each other, said stem being in communication with said air inlet passage whereby the said valve is subjected to air pressure at the base of said stem, said chamber being adapted to receive air through said orifices whereby air pressure is applied against said check valve within said chamber, 15
 guide means associated with said sleeve for supporting said stem for reciprocating movement, a compression coil spring about said stem between said sleeve and said abutment means of said stem urging the check valve to a closed position against the valve seat, 20
 said check valve assembly being adapted to be opened in response to air pressure supplied through said terminal air inlet passage whereby air is injected into the combustion chamber through said center electrode and said spark plug. 25
